PORTABLE GRAVE LINER

Robert W. Talley, Clarendon, Tex.

Application June 1, 1932, Serial No. 614,743

1 Claim. (Cl. 61—41)

This invention relates to devices for lining graves or the like and particularly to a liner which may be kept in stock by undertakers and which may be readily carried to the grave and 5 inserted in the grave so as to line the walls thereof.

A further object is to provide a portable grave liner which may be made up in different dimensions to accommodate various sizes of caskets and which is molded in one solid piece of concrete 10 cured and kept in stock as are other undertakers' supplies.

Another object is to so construct the grave liner as regards its details that it shall be particularly strong and thoroughly reinforced while 15 at the same time being relatively light.

Other objects will appear in the course of the following description.

My invention is illustrated in the accompanying drawing, wherein:—

20 Figure 1 is a perspective view of a grave liner constructed in accordance with my invention;

Figure 2 is a vertical sectional view through one of the walls of the liner;

25 Figure 3 is a fragmentary horizontal section on the line 3—3 of Figure 1.

Referring to the drawing, 10 designates the grave liner generally which is rectangular in plan to provide opposed side walls and opposed end walls. These side and end walls are formed 30 preferably of integral molded concrete. Inasmuch as the end walls and side walls are alike, a description of one of these walls will apply to all of the walls.

Each wall of the liner has a smooth outer 35 face 11. The inner face is formed with longitudinally extending recesses 12 defined by outwardly projecting ridges or ribs 13. The recesses 12 will terminate short of the junction of one of the walls with the next adjacent wall as shown in

40 Figure 3. The recesses 12 may have any desired depth and any desired width. Ordinarily the recesses will have a width of approximately four inches and have a depth of approximately two inches. The ribs defining said recesses are re-

45 forced by the longitudinally extending reinforcing bars 14 which extend to the end of the wall but do not project beyond the edge of the wall, that is, beyond the surface of the liner. The body of each wall is reinforced inward of

50 the ribs and rests by means of any desired reinforcing elements, though I have shown for this purpose a reinforcing element of intersecting wires, as for instance, a wire fabric designated 15.

55 It will be seen that inasmuch as the ribs and recesses of any one wall terminate short of the

adjacent walls, the corners of the structure will be the full thickness so as to provide what may be termed corner posts, thus giving support to any weight which may be placed upon the top of the liner. Preferably the system of ribs and recesses will begin with a rib at the top of the grave liner wall and end with a rib at the bottom of the wall.

In actual practice, the width of the ribs will be approximately 1½ inches. The longitudinally extending grooves or recesses of the inner face of the liner wall eliminate from 40% to 50% of the weight, cost of materials and the labor of making a solid wall liner while at the same time they greatly increase the strength of the wall. It 60 will be seen that I have provided a portable grave liner which is as strong and durable as grave liners made in situ. This grave liner is simple to design, extremely durable and provides an absolute protection from the caving in of the grave 65 walls, particularly in view of the fact that the liner may be fully cured before being inserted whereas where plastic cement is used for lining the grave opening, it may be and usually is not allowed to set properly before the grave is used 70 75 and thus is not fully cured.

I claim:

As an article of manufacture, a grave liner rectangular in plan and open at the top and bottom and entirely unobstructed throughout its 80 entire interior, and formed of one integral piece of concrete, the inner face of each wall of the liner having a plurality of longitudinally extending recesses defined by intermediate ribs, the recesses terminating short of the corners of the liner, and the uppermost recesses being below the top of the liner, whereby the top edge of the liner is of full thickness and whereby the corners of the liner are of full thickness, and reinforcing elements embedded in the concrete of the liner. 85 90 95
